UNITED STATES PATENT OFFICE.

WADE H. MCINTOSH, OF XENIA, OHIO.

DESIGN FOR A PUNCTURE-PREVENTER FOR BICYCLES.

SPECIFICATION forming part of Design No. 32,255, dated February 20, 1900.

Application filed January 23, 1900. Serial No. 2,547. Term of patent 3½ years.

To all whom it may concern:

Be it known that I, WADE H. MCINTOSH, a citizen of the United States, residing at Xenia, in the county of Greene and State of Ohio, have 5 invented a new and useful Design for a Puncture-Preventer for Bicycles, of which the following is a specification, reference being had to the accompanying drawing, forming a part thereof.

By reference to the drawing it will be seen that the material feature of my design consists of an elongated strip having parallel upper and lower flat faces *a* and *b* and front and rear edges *c* and *d*, bent into the form of half 5 an ellipse. The rear edge *c* is plain, while the front edge *d* is serrated, resulting in teeth *e*, extending in the plane of the upper and lower faces *a* and *b*. At each end of the strip is a

pair of ears *f*, extending outwardly from the upper face *a* at right angles thereto and based 20 upon the front and rear edges *c* and *d*, respectively. The ears *f* are flat and have parallel edges connected by arcs at their outer extremities, and each of which pairs of ears is provided with a perforation *g* at its center. 25

Having thus described my invention, what I desire to secure by Letters Patent is—

The design for a puncture-preventer for bicycles, as herein shown and described.

In testimony whereof I sign my name in the 30 presence of two subscribing witnesses.

WADE H. MCINTOSH.
